UNITED STATES PATENT OFFICE.

FREDRICK E. JOSS, OF BROOKLYN, NEW YORK, ASSIGNOR TO LEKTOPHONE CORPORATION, A CORPORATION OF DELAWARE.

STYLUS-HOLDER FOR TALKING-MACHINES.

1,359,995.

Specification of Letters Patent. Patented Nov. 23, 1920.

Application filed January 22, 1919. Serial No. 272,408.

To all whom it may concern:

Be it known that I, FREDRICK E. Joss, a citizen of the United States, residing at 5 borough of Brooklyn, in the county of Kings, State of New York, have invented certain new and useful Improvements in Stylus-Holders for Talking-Machines; and I do hereby declare the following to be a full, clear, and exact description of the invention, such as will enable others skilled in the art to which it appertains to make and use the same.

This invention relates to talking machines, and in particular to machines of the Hopkins type, in which the vibrations of the stylus, during its travel along a phonic line, are transmitted to a conical diaphragm of large area, freely supported in unconfined air, in a manner to move the entire conical 20 portion of the diaphragm bodily.

In machines of the character specified, the diaphragm is usually attached to the rear end of a supporting bar, which is mounted to move across the record, and carries a vibration transmission connection that extends from the stylus to the diaphragm. Such connection preferably comprises, in addition to the stylus holder, a transmission rod or element which is received within a bore or 25 passage extending through the supporting bar from end to end thereof and is joined at its front end to the holder and at its rear end to the apex of the diaphragm. Ordinarily, the mounting of the stylus holder is such that the stylus will operate effectively 30 only in connection with either lateral-cut or hill-and-dale records, thus limiting its use to one or the other of these two types of record. It has been proposed to overcome 35 this difficulty by providing a transmission connection capable of movement from a position for playing records of one character to a position in which records of the other character can be played, and vice versa. 40 This was effected by mounting the supporting bar to turn about its longitudinal axis, carrying with it the diaphragm and transmission connection, the stylus being thereafter movable relatively to the transmission 45 rod so as to properly position it for engage-

ment with the record. The independent or relative movement of the stylus was permitted by constructing the holder in two parts, the part which carried the stylus being mounted to rotate on the other part or 55 base of the holder, to which the transmission rod was attached.

According to the present invention the former universal mounting is simplified, and at the same time improved, by utilizing a 60 stylus holder which, instead of being made in two parts, as before, consists of a single part only which is mounted in the supporting bar and connected with the transmission rod in such a manner that it can adapt itself 65 with equal facility to both types of vibrations. In this way, the actual cost of construction is decreased, while any danger of the stylus-carrying part of the holder working loose upon the base of the holder is 70 avoided, so that a more effective construction is provided than the one formerly utilized.

The invention further resides in the provision of a one-piece stylus holder having 75 the characteristic features above indicated, which is mounted in the supporting bar in a manner such as will enable it to be adjusted with respect thereto for the purpose of enabling the sensitiveness of the diaphragm to be controlled. A mounting of the general character proposed is illustrated in a prior U. S. Patent 1,312,958, granted August 12, 1919, in the names of William H. Davis and myself as joint inventors. In the 80 construction shown in that patent, a resilient mounting is provided for the stylus holder, constituted by a spring which is received in a socket formed in the end of the supporting bar, and which is capable of being drawn 85 out from or pushed back into its socket for the purpose of varying the length of its exposed portion. This spring, however, is flat, and for that reason can flex in one direction only, that is, a lateral flexion in the 90 plane in which it lies. Such flexion precluding the playing of hill-and-dale or vertical-cut records. In the present construction, the flat spring is replaced by a strip of wire 95 preferably of circular section, which may be 100

moved into or out of its socket, and may be clamped in adjusted position, and the arm or extension on the vertical base portion of the holder to which the transmission rod 5 is connected is disposed at an angle which may vary from 37° to 45° to the vertical plane passing through the longitudinal axis of the stylus-carrying part of the holder, instead of being arranged at an angle of 90° 10 to the holder as was formerly the case. With the improved construction, it is possible for such plane to vibrate both laterally for zig-zag cut records, and vertically for hill-and-dale records, so that either type of record 15 can be played without entailing any change in the position of the stylus or any manipulation of the supporting bar.

The accompanying drawing illustrates one form which the invention may take in practice, and therein:

20 Figure 1 is a side elevation of the improved stylus holder, applied to a supporting bar, the latter appearing in dotted lines;

25 Fig. 2 is a front view, but the bar is shown herein in full lines;

Fig. 3 is a perspective view of the holder;

30 Figs. 4 and 5 are horizontal and vertical sectional views taken, respectively, on line 4-4 of Fig. 2 and 5-5 of Fig. 4, looking in the direction of the arrows; and

35 Fig. 6 is a fragmental vertical sectional view on a reduced scale, showing the diaphragm mounted on the supporting bar and connected to the transmission rod.

40 While the form of the invention disclosed in the drawing may be regarded for present purposes as preferred, yet the invention is not intended to be limited to the precise structural details of such disclosure. On the contrary, the invention is clearly susceptible 45 to modification and change while still falling within the scope of the appended claims.

45 In the construction disclosed in the drawing, 1 indicates generally the supporting bar, and 2 the transmission rod of a Hopkins-type talking machine. The bar 1 is mounted to move across the turn table of the machine in the usual way, and it carries at its rear end a large, conical diaphragm 17 (Fig. 6), which is freely supported in unconfined 50 air and which has connected to its apex the rear end of the transmission rod. The latter is disposed within an eccentric bore 3, which extends through the bar from end to end, the ends of the rod projecting through the 55 opposite ends of the bore. These parts are usual in Hopkins machines, and, hence, require no extended description.

60 The improved stylus holder 4, wherein the present invention essentially resides, is of one-piece construction, as previously stated, and comprises a base 5 and a downwardly-inclined, stylus-carrying part 6, the latter having an enlarged head 7 in which the stylus 8 and the clamping screw 9 are 65 mounted in the ordinary manner. To the

center of the base 5 of the holder there is rigidly secured the forward end of a small metal strip or section 10. This strip 10 is made of spring wire of circular section, and it fits in a similarly shaped 70 socket 11 which is formed axially in the supporting bar 1 and opens through the front end thereof. It may be drawn out of or pushed back into its socket to vary the length of its exposed portion, as presently 75 explained, and it may be retained in adjusted position by suitable clamping means, here shown as comprising a pair of screws 12 which are inserted in threaded recesses 13 formed radially in the bar, the ends of the 80 screws engaging small wooden bearing blocks 14 which likewise fit in the threaded passages or screw holes 13 and which directly engage the spring wire strip at their inner ends, at which point they are preferably concaved so as to conform to the curvature of the strip and thus provide an increased gripping surface. By tightening the screws, their pressure against the bearing blocks is, of course, increased, with the 85 result that the wire strip will be firmly 90 clamped in place. At the same time, by providing the bearing blocks, the screw ends are prevented from engaging and possibly injuring the wire strip.

95 There is also formed on the base 5, of the holder, an arm or ear 15, to which the front end of the transmission rod 2 is secured, the arm being preferably slotted longitudinally, as indicated at 16, to enable the adjustable attachment of the rod end thereto, such attachment being effected in the manner disclosed in the Davis and Joss patent, above identified, or in any other suitable manner. This arm 15, instead of being disposed at an 100 angle of substantially 90° to the vertical plane which passes through the longitudinal axis of the stylus carrying part 6 of the holder, is disposed at an acute angle to such plane which may vary between 37° and 45° , the former arrangement being disclosed. 105

110 The spring wire strip 10, as will be understood from the foregoing, provides a resilient mounting for the stylus holder, and by reason of the employment of a strip which is capable of flexing either vertically or laterally, as distinguished from a flat or leaf spring, and of the disposition of the attaching arm 15 in the manner indicated, both transverse and vertical vibrations may be 115 imparted with equal facility to the stylus and its holder, according as one type of record or the other is being played, and transmitted by the rod to the diaphragm. Thus both standard types or record may be 120 played interchangeably, without entailing any manipulation of either the supporting bar or the holder other than that ordinarily required for the insertion and removal of stylus. The adjustment of the spring strip affords means for experimentally locating 125 130

and establishing a particular and very precise resiliency in the exposed length of the spring, with a resultant control of the sensitiveness of the diaphragm 17, in the same 5 way as in the earlier construction disclosed in the Davis and Joss patent. In other words, if the wire strip or spring is drawn out of its recess, the resiliency of its exposed portion is necessarily increased and the 10 holder will then vibrate with a greater degree of freedom; if the spring is pushed back in its recess, then the length of its exposed portion is decreased and the exposed portion is rendered stiffer and can vibrate with less 15 freedom. This is necessitated, of course, by possible variations in the thickness of the diaphragm, and in actual practice an adjustment is made for the particular diaphragm that is being used. The adjustment of the 20 spring, as above described, entails a corresponding adjustment of the diaphragm 17, and its supporting frame 18, the latter being connected to the supporting bar by means of the spider 19, the hub 20 of which fits 25 on the supporting bar and is loosened before the adjustment of the spring takes place. When the spring is being adjusted, the diaphragm frame and the diaphragm will move with the transmission rod, and at the completion 30 of the adjustment, the spider hub 20 is retightened. The necessity for this double adjustment is due to the fact that if the diaphragm frame were rigid on the supporting bar, changes in the disposition of the spring 35 would occasion a positive tension or pressure being imposed or exerted upon the diaphragm, which is not desirable.

I claim as my invention:—

1. In a phonograph transmission, the combination of a supporting bar; a diaphragm 40 attached to said bar at its rear end, a stylus holder at the front end of the bar, a spring support connecting the holder to the bar and capable of flexing in both horizontal and 45 vertical planes so as to permit the holder to vibrate both laterally and vertically, and a vibration transmission element disposed longitudinally of the bar and connected at its rear end to the diaphragm and at its 50 front end to the holder at a point offset from the axis of vibration and lying between a vertical and a horizontal plane passing through the longitudinal axis of the vibration transmission member so that either vertical or lateral vibrations of the holder will 55 be transmitted to the diaphragm.

2. In a phonograph transmission, the combination of a supporting bar; a diaphragm attached to said bar at its rear end; a stylus 60 holder at the front end of the bar having an arm which is inclined at an acute angle to the vertical plane passing through the longitudinal axis of the holder; a vibration transmission element disposed longitudinally of 65 the bar and connected at opposite ends with

said diaphragm and said arm; and a support for the holder consisting of a strip of spring wire which connects the holder to the adjacent end of the bar and which is adapted to flex in both horizontal and vertical planes 70 so as to permit the holder to vibrate both laterally and vertically.

3. In a phonograph transmission, the combination of a supporting bar; a diaphragm attached to said bar at its rear end; a stylus holder at the front end of the bar provided with a vertical base portion and with an arm which is rigid with and disposed in the plane of said base portion and which is inclined at an acute angle to the vertical 80 plane which passes through the longitudinal axis of the holder; a vibration transmission element disposed longitudinally of the bar and connected at opposite ends with said diaphragm and said arm; and a support for 85 the holder consisting of a strip of spring wire which connects the holder to the adjacent end of the bar and which is adapted to flex in both horizontal and vertical planes so as to permit the holder to vibrate both 90 laterally and vertically.

4. The combination of a stylus holder, and a support therefor comprising a strip of spring wire attached at its forward end to the rear end of the holder and adapted to 95 flex in both horizontal and vertical planes so as to permit the holder to vibrate both laterally and vertically; a diaphragm and a vibration transmission element connected at one end to the diaphragm and at the other 100 end to the holder at a point offset from the axis of vibration and lying between the vertical and horizontal planes of vibration of the holder; substantially as described.

5. The combination of a stylus holder having a vertically disposed, plane face, and a support therefor comprising a strip of spring wire fixed at its forward end to the center of said face and adapted to flex in both vertical and horizontal planes so as to 105 permit the holder to vibrate both laterally and vertically, a diaphragm and a vibration transmission element connected at one end to the diaphragm and at the other end to the holder at a point offset from the axis 110 of vibration and lying between the vertical and horizontal planes of vibration of the holder; substantially as described.

6. The combination of a stylus holder having a base at its rear end and an arm lying 120 in the plane of said base and disposed at an angle to the vertical plane which passes through the longitudinal axis of the holder, and a support for the holder comprising a strip of spring wire fixed at its forward end 125 to said base and adapted to flex in both horizontal and vertical planes so as to permit the holder to vibrate both laterally and vertically; substantially as described.

7. The combination of a stylus holder hav- 130

ing a base at its rear end and an arm lying in the plane of said base and set at an acute angle to the vertical plane which passes through the longitudinal axis of the holder, 5 and a support for the holder comprising a spring member of circular cross section fixed at its forward end to said base and adapted

to flex in both horizontal and vertical planes so as to permit the holder to vibrate both laterally and vertically; substantially as de- 10 scribed.

In testimony whereof I affix my signature.

FREDRICK E. JOSS.
